Attorney

UNITED STATES PATENT OFFICE.

JUAN DIEGO SHAW, OF BUENOS AIRES, ARGENTINA.

DEVICE FOR AVOIDING THE TWISTING OF ELECTRIC WIRES.

1,238,448.

Specification of Letters Patent. Patented Aug. 28, 1917.

Application filed October 7, 1916. Serial No. 124,370.

To all whom it may concern:

Be it known that I, JUAN DIEGO SHAW, citizen of Argentina, residing at No. 870 Venezuela St., Buenos Aires, Argentina, have invented certain new and useful Improvements in Devices for Avoiding the Twisting of Electric Wires, of which the following is a specification.

My present invention relates to a special device for avoiding the twisting of electric leads or wires, and the main object of the same is to untwist said wires when twisting or coiling has already taken place, without necessity of cutting off the current, in some cases, and without interrupting the contacts which may have been established.

The device according to this invention may be applied indifferently to wall sockets, telephone receivers and the like, where the wires or leads are liable to twist, with the consequent inconvenience.

This difficulty may be avoided, in accordance with the present invention, by making one portion of the device rotary, independently of the other, and arranging within the same the means necessary to prevent the contact from being broken while one of the said parts is made to revolve with respect to the other.

In order that the invention may be clearly understood and carried into practice without difficulty, one of its forms is illustrated, by way of example, in the accompanying drawings, wherein:

Figure 1 is a central longitudinal section of a plug constructed in accordance with the present invention.

Fig. 2 is a perspective view of the portion of the same plug which is applied to the socket.

Figs. 3 and 4 are perspective views of intermediary rings, made of any suitable conducting material and which are designed to maintain the contacts, and

Fig. 5 is a perspective view of the remaining part of the plug which forms the rotary portion.

In all these drawings the same reference numerals indicate the same or corresponding parts.

It will be evident that although the draw-

ings represent a plug and the following description is substantially limited thereto, the device may take any other suitable form, in accordance with the particular use for which it may be designed, without departing from the basis of this invention, the essential features of which are clearly determined in the final claims annexed to this specification.

Other modifications might also be introduced without going beyond the scope of the invention.

1 is a cylindrical piece of ebonite or any other suitable insulating material, provided at its base with the contact pieces 2 and 3, partially covered with insulating material 4 and designed to establish contact with the terminals of the socket in the usual manner. When the device is not used for a plug, the contact pieces 2 and 3 may adopt any other suitable form for receiving the electric wires or leads. The contact piece 2 of one of the terminals is electrically connected to a metallic screw 5, the other end of which is screwed into a conducting piece 6, fixed in its turn, by means of a screw 8 to a metallic ring 7 placed in a cavity in the cylindrical body 1 and insulated by an annular rib or shoulder 12, between which latter and a central, cylindrical rod-like lug or projection 12' there is produced a recess which will be described later.

The contact piece 3 is electrically connected, by a screw 9, to another metallic ring 10, encircled by an annular rib or shoulder 11, and between this rib 11 and the rib 12, aforesaid, there is also formed an annular space or recess.

The inner face of the cylindrical body 1 is threaded as indicated at 25, so as to screw on to the cap 24, also made of ebonite or any other suitable insulating material and which serves as support for the rotary piece 23.

The said rotary piece 23, also constructed of ebonite or any other convenient insulating material, is substantially cylindrical in shape and has an enlarged inner end portion so as to permit of the cap 24 holding it to the cylindrical body 1, without impeding the movement of the rotary piece 23 with respect to the said cap 24 and to the body 1 which remain fixed and are held together

by the screw joint 25 or by means of screws or in any other convenient manner. Between the enlarged inner end of the piece 23 and the cap is a space in which is placed a 5 spring designed to maintain free play between both pieces, as shown at 26.

Inside the rotary portion 23 is a central rod-like lug or projection 27 which in diameter and position corresponds to the central 10 projection 12' of the fixed body 1, with which it comes into contact; there are also formed two annular ribs or shoulders 13 and 14, the positions and thicknesses of which respectively correspond to those of 15 the ribs 11 and 12, above mentioned. Between the ribs 13 and 14 and between the latter and the central projection 27 are annular spaces or recesses which form extensions of the similar recesses in the cylindrical 20 member 1, between the ribs 11 and 12 and between this latter and its central projection 12'.

At the bottom of the recesses between the ribs 13 and 14 and between the latter and 25 its central projection 27 are arranged metallic conducting rings, 18 and 17 respectively, and the remainder of said recesses is filled by the independent intermediary rings 15 and 16 respectively. Said rings are made 30 of conducting material and form contact between the rings 10 and 18 and the rings 7 and 17 respectively, of the device in accordance with the invention.

The ring 17 is connected by means of a 35 metallic screw 22 or in any other suitable manner to one of the ends of the outgoing wire or lead 28, while the contact ring 18 communicates, by means of a supplementary angular portion 19 joined by a screw 20 to 40 another screw 21, with the opposite lead 29. The contacts of the wires may be inclosed within the same cap or an additional cap may be provided for them.

The operation of the device will be readily 45 understood as it will be evident that without necessity of withdrawing the plug from its socket, the rotary portion 23 may be turned as much as may be needful to untwist the wire, without thereby interrupting 50 the contacts, as these latter are circular and the intermediary rings operate in any position.

Although in the drawings only a plug for 55 two wires has been illustrated, it will be evident that the device in accordance with this invention may be used in connection with any number of leads and for that purpose it will only be necessary to provide in each case the corresponding number of conductive 60 tact rings and intermediary rings.

Also other modifications may be introduced, as regards the construction and arrangement of parts, without departing from the limits of the invention, the substantial

features of which will now be set forth in the appended claims.

I declare that what I claim as new and desire to secure by Letters Patent, is:

1. An electrical connection of the character specified, comprising, in combination, a pair of companion members, one of which embodies a sleeve-like cap rigidly connected to the other member and having an axial opening, and a freely-rotatable part having an enlarged inner end disposed within said cap in confronting relation to said other member and a substantially-cylindrical body projecting axially outward through said opening; the confronting faces of said other member and said rotatable part being provided, each, with a pair of spaced, concentric annular ribs and with a central projection disposed within and encircled by the inner rib; the ribs and projection of said members being located directly opposite each other; a separate conducting ring disposed in the space between the outer and inner ribs of each member; a separate conducting ring disposed in the space between the inner rib and central projection of each member; conducting wires leading to the rings of said rotatable part; a pair of contact pieces located exteriorly of said other member and connected, each, to one of the rings thereof; outer and inner conducting means interposed one between the two outer rings and the other between the two inner rings and in sliding contact with the same; and spring means disposed within the first-mentioned member between the enlarged end of said rotatable part and the adjacent wall of said cap, to press the former axially inward toward said other member, so as to constantly maintain the said rings electrically connected by said interposed conducting means during the rotary movements of said rotatable part.

2. An electrical connection of the character specified, comprising, in combination, a pair of companion members, one of which embodies a sleeve-like cap rigidly connected to the other member and having an axial opening, and a freely-rotatable part having an enlarged inner end disposed within said cap in confronting relation to said other member and a substantially-cylindrical body projecting axially outward through said opening; concentric outer and inner conducting rings secured to the confronting end faces of said outer member and said rotatable part, the rings on each of said faces being located directly opposite those on the other face; conducting wires leading to the rings of said rotatable part; a pair of contact pieces located exteriorly of said other member and connected, each, to one of the rings thereof; concentric outer and inner conducting means interposed one be-

tween the two outer rings and the other between the two inner rings and in sliding contact with the same; and spring means disposed within the first-mentioned member 5 between the enlarged end of said rotatable part and the adjacent wall of said cap, to press the former axially inward toward said

other member, so as to constantly maintain the said rings electrically connected by said interposed conducting means during the rotary movements of said rotatable part. 10

In testimony whereof I affix my signature.

JUAN DIEGO SHAW.
